2,502,580

ELECTRICAL CIRCUITS FOR MOTOR VEHICLES

Sherman A. McMillan, San Francisco, Calif.

Application June 16, 1945, Serial No. 599,826

3 Claims. (Cl. 123—179)

1

The present invention relates to improvements in electrical circuits for motor vehicles, including sea and aircraft, and its principal object is to introduce certain safety features whereby fire hazards are substantially eliminated.

For this purpose it is principally proposed to provide means whereby the main battery circuit is broken at all times when the vehicle is at rest. Many fires occur due to shorts developing while the vehicle is put away in the garage overnight or otherwise left unattended for extended periods of time.

In the present invention it is proposed to provide a separate switch in the main electrical circuit, somewhere near the battery, and to arrange the switch in such a manner that it automatically opens when the conventional ignition switch is turned off.

It is further proposed to arrange the switch so that it requires the closing of the conventional starter switch to again close the separate switch, in order that the latter when open, remains unaffected by the mere closing of the ignition switch.

And finally, I propose to provide means whereby the separate switch is made to remain closed, after the starter switch has been released, as long as the conventional ignition switch remains closed.

It is a still further object of my invention to provide against fire hazards due to collision and due to the overturning of the motor vehicle, by causing a break in the main ground circuit of the battery, whereby the entire electrical system is rendered inactive and all danger of shorts is eliminated.

Further objects and advantages of my invention will appear as the specification proceeds, and the novel features of my electrical circuit will be fully defined in the claims hereto attached.

The preferred form of my invention is illustrated in the accompanying drawing forming part of this application, in which:

The one figure shows a wiring diagram illustrating my circuit.

While I have shown only the preferred form of the invention, it should be understood that various changes or modifications may be made within the scope of the claims hereto attached without departing from the spirit of the invention.

Referring to the drawing in detail, the conventional storage battery 1 is shown as being connected, on the positive side, to the starting motor 2 through wire 3.

2

At the motor, the wire divides into two branches, one passing through the starter switch 4 and the motor windings to the ground, as at 5, while the other is the main electrical circuit and includes the wire 6, armature 6', the switch 7, which is normally open, the wire 7', the windings 8 of an overload solenoid, a movable switch member 9 which normally contacts a stationary switch member 10, and a wire 11 leading to the ammeter 12.

10 Beyond the ammeter the ignition circuit comprises a wire 13, the conventional ignition switch 14 and wire 15 leading to the ignition coil primary and thence to the ground, in the conventional manner.

15 The negative side of the battery is connected to the ground, as indicated at 16, through wire 17 which contains the switch 18, normally closed.

One of the principal features of the present invention is the switch 7, which is normally open, and which breaks the main electrical circuit, preferably near the battery, unless it has been closed by operation of the starter switch.

The starter switch 4 is connected, through wire 19, with a relay 20, grounded as at 21, which latter closes, when energized, a switch 22, in a line 23 leading from wire 19 to the solenoids 24 and the ground, as at 25. The solenoids, when energized, close the switch 7, so that the latter is closed whenever the starter switch is depressed for starting the engine.

Assuming that the operator, before pressing the starter switch, has closed his ignition switch, the solenoids 24 will continue to be fed, for maintaining switch 7 closed after the starter switch has been released, through wire 26, which leads from the ignition switch past the gas gauge 27 to the wire 23 and the solenoids.

When the ignition switch is opened, switch 7 automatically opens, and it remains open, even if the ignition switch is closed thereafter. The switch 7 is only closed when the starter switch is operated and thereupon is maintained in closed position through current flowing through the ignition switch, so that it remains closed as long as the ignition switch is closed.

In case it is desired to operate equipment, such as light or radio, while the vehicle is standing idle and the ignition switch is turned off, I provide a shunt circuit 28 for the switch 7, the shunt preferably including a fuse 29 and a switch 30 subject to manual control.

50 In case of accident and collision of the motor vehicle, shorts naturally develop, causing a heavy flow of current through the overload solenoid 8,

This solenoid is designed to become active at a predetermined overload, so as to break the switch 9-10 and to move switch member 9 into contact with a switch member 35, closing a circuit leading from the battery 1 through wires 3, 6, 7', and thence through wire 36 to a solenoid relay 37 and the ground, as at 38.

The overload solenoid has a lock-out device 8 comprising two dogs 60 engaging in a groove 61 for holding the armature 9 in contact with contact 35.

Since the breaking of the switch 9-10 would allow switch 7 to open, I provide a fuse 63 across the contacts to maintain current flow through 11, 12, 13, 14, 26, 23 to solenoid 24 for a brief period which will keep switch 7 closed until switch 18 has opened, as described in the next paragraph.

The solenoid 37 closes a switch 39, which causes a current to flow from wire 6 through wires 40, 41 and 42 to the solenoid 43 and the battery through wire 17. The solenoid breaks the switch 18, thus opening the main electrical connection for the battery to the frame. The core of the solenoid is held in switch-opening position by a pair of hinged dogs 64 engaging in the indentations 65.

The latter connection is further protected against a heavy surge of current by a thermostat control including a bimetallic strip 46, which opens a switch (not shown) in case of excessive heat.

The circuit last described may also be used for closing a valve 48 in the fuel line 49 coming from the gas tank 50 through a lever 51 operated by a solenoid 52 forming part of a shunt circuit 53 branching off from wire 41, and grounded as at 54.

To guard against fire hazards due to overturning of the motor vehicle, I provide a mercury switch 55 shunted across switch 7, and connected by wires 56 and 57, to wires 40 and 36, respectively.

In case the motor vehicle overturns, the mercury switch closes, and causes a current to flow from the battery 1 through the solenoid 37, closing switch 39 and breaking the main battery ground connection at 18.

After a collision, if the engine should continue to keep running the generator shown at 58, I introduce a relative low amperage fuse 59, responsive to about six amperes, in the generator field circuit, which will render the generator inoperative when the fuse burns out.

Where magneto ignition is used, as in airplanes or any system using dual ignition or a combination of battery and magneto ignition, I use the armature 9 to operate a second contact 70 and push it against insulated contact 71, thereby grounding line 72 leading to an insulated member of breaker contacts 73 on the magneto or battery primary 74 on the magneto armature 75.

When the primary is thus grounded on both sides, no spark will be induced in the secondary winding. Switch 70-71 might be used in the same manner to short-circuit the primary circuit of a conventional distributor.

I claim:

1. In an electric circuit for a motor vehicle, a source of electrical energy, an ignition switch, a line connecting the source with the ignition switch and having a safety switch therein, an electro-magnet for operating the safety switch,

and a by-pass from said line connected to the electro-magnet and having a switch therein for energizing the magnet when the switch is closed, the said line being continued beyond the ignition switch and connected to the by-pass between the by-pass switch and the electro-magnet.

2. An electrical circuit for a motor vehicle having a battery, a starting motor with a starting switch, an ammeter, an electrical lighting system and an ignition system, the circuit comprising a main line connecting the positive side of the battery to the lighting system and having the ammeter incorporated therein, a branch line connected to the main line below the ammeter and leading to the ignition system, an ignition switch in said branch line, a normally open safety switch in the main line between the battery and the ammeter and having an electro-magnet for closing the same, a second branch line connected to the main line between the battery and the safety switch and having the starting switch therein and being connected to the electro-magnet for closing the safety switch when the starting switch is closed, and a third branch line connected to the first branch line below the ignition switch and to the electro-magnet for maintaining the safety switch closed as long as the ignition switch is closed, but allowing the safety switch to open when the ignition switch is opened.

3. An electrical circuit for a motor vehicle having a battery, a starting motor with a starting switch, an ammeter, an electrical lighting system and an ignition system, the circuit comprising a main line connecting the positive side of the battery to the lighting system and having the ammeter incorporated therein, a branch line connected to the main line below the ammeter and leading to the ignition system, an ignition switch in said branch line, a normally open safety switch in the main line between the battery and the ammeter and having an electro-magnet for closing the same, a second branch line connected to the main line between the battery and the safety switch and having the starting switch therein and being connected to the electro-magnet for closing the safety switch when the starting switch is closed, and a third branch line connected to the first branch line below the ignition switch and to the electro-magnet for maintaining the safety switch closed as long as the ignition switch is closed, but allowing the safety switch to open when the ignition switch is opened, the second branch line having a relay between the starter and the electro-magnet to protect the starter from current flowing through the third branch line.
